UNITED STATES PATENT OFFICE.

CLARENCE B. WESTON, OF ERIE, PENNSYLVANIA, ASSIGNOR, BY MESNE ASSIGNMENTS, TO BUCYRUS-ERIE COMPANY, OF SOUTH MILWAUKEE, WISCONSIN, A CORPORATION OF DELAWARE.

FLUID-ACTUATED ENGINE.

Application filed April 24, 1926. Serial No. 104,290.

This invention is designed to control fluid-actuated engines so as to positively reverse them in a simple manner. In the preferred form the reversal is accomplished simultaneously with the operation of the throttle, thus adapting the device to such engines as are used for excavating machines and similar devices where the reversal factors are of great importance. The controlling mechanism is preferably mounted on the engine shaft and in the present invention is housed in a cylindrical carrier which has some fly wheel action, the carrier properly housing the mechanism. In carrying out the invention a double fluid-actuated control is provided so that the eccentric is positively positioned in both directions through the pressure of the fluid-actuated means. Details and features of the invention will appear from the specification and claims.

The invention is illustrated in the accompanying drawings as follows:—

Fig. 1 shows a plan view.

Fig. 2 a side elevation, partly in section.

Fig. 3 a sectional view through the devices on the line 3—3 in Fig. 4 showing the fluid actuated controlling means.

Fig. 4 a section on the line 4—4 in Fig. 3.

Fig. 5 a sectional view of the throttle and controlling valve, the throttle being closed and the valve setting the engine to a forward direction of movement.

Fig. 6 a similar view with the throttle valve slightly opened and the controlling valve in a position for a forward movement of the engine.

Fig. 7 a section on the line 7—7 in Fig. 4.

Fig. 8 a diagram showing the relative crank and eccentric positions for Fig. 3.

Fig. 9 a sectional view of the controlling mechanism on the line 9—9 in Fig. 10, the mechanism being set to drive the engine in a reverse direction.

Fig. 10 a section on the line 10—10 in Fig. 9.

Fig. 11 a sectional view of the throttle and controlling valve in position to throw the controlling mechanism to the position of Fig. 9.

Fig. 12 a sectional view of the throttle and control valve in position for reverse movement as indicated in Fig. 9, the throttle valve being slightly open.

Fig. 13 a diagram indicating the relative crank and eccentric positions of Fig. 9.

Fig. 14 is a section on the line 14—14 in Fig. 11.

1 marks the frame of the engine, 2 the cylinders, 3 the valve chest, 4 the crank shaft, 4^a the cranks, 4^b bearings for the crank shaft, 5 connecting rods, 6 cross heads, 7 cross head guides, 8 piston rods, 9 pistons, 10 steam ports leading from the cylinder to the engine valve chamber 11, 12 steam passages leading from the chamber 11 through a port 13 to the throttle valve chamber 14, 15 exhaust ports leading from the valve chamber 11, 16^a the end elements of the engine valve 16, said elements operating across the ports 10 and 15, 17 the center element of the valve operating over the ports or passages 12. This is the ordinary cylindrical engine valve construction cutting off the fluid on the inner end of the end element 16^a. Valve rods 18 and 19 lead from the valves 16. The rod 18 is connected with a rocket 20 formed on a sleeve 21. The sleeve 21 is carried in a bearing 22 and is provided with a rocker 23. The rocker 23 is connected by an eccentric rod 24 with an eccentric strap 25 and the eccentric strap is mounted on an eccentric 26. The rod 19 has a rocker 27 carried by a shaft 28. The shaft 28 extends through the sleeve 21 and has a rocker 29 at its outer end. The rocker 29 is connected by a link 30 with a bell crank lever 31. The bell crank lever 31 is mounted on a pin 32 and is connected by a link 33 with the eccentric 26 operating at 90° from the rod 24 so as to operate the engines with the angular relation of the cranks as indicated.

Thus it will be seen that the link 33 is quartering to the rod 24 and as the cranks are set quartering the valve movement for each engine is timed properly with the quartering cranks and that the throwing of the eccentric for one of the engines throws the eccentric for the other of the engines and that varying the eccentric with relation to the crank shaft similarly varies the throw for both cylinders.

A throttle valve 34 is of a sliding type operating in a valve face 34^a in the chamber 14. It has ports 35 and 36 extending through it and each of these ports is adapted to be brought into register with the port 13 lead-

ing to the valve chamber 11. Either of the ports 35 or 36 deliver steam, or fluid to the engine, the purpose of the two ports being to give the throttle two separate openings so that the throttle may be connected with the controlling means for positioning the eccentric. Fluid is delivered to the chamber 14 through a pipe 14^a and the valve 34 is connected by a valve rod 34^b with an operating lever 34^c.

A carrier 37 is mounted on the end of the crank shaft. The carrier is fixed on the shaft by a key 37^a. A rock shaft 38 is journaled in the walls of the carrier, the carrier being hollow. The eccentric is mounted on the inner end of the shaft and keyed on the shaft by means of a key 40. A rock lever 41 is carried by the shaft 38 and locked therewith by a key 42 and set screw 42^a. Rods 43 are secured to opposite ends of the rock lever 41 by pins 44. These rods are connected with pistons 45 by ordinary pivotal connections (not shown). The pistons are arranged in cylinders 46 and 47. These cylinders are cast in block and secured to the carrier by bolts 46^a. The outer end of the block carrying the cylinders is cylindrical with the shaft as a center.

The cylinder 46 is connected by a port 48 with a radial passage 49 in the crank shaft and the radial passage extends into an axial passage 50. The cylinder 47 is connected by a port 51 with a radial passage 52 in the crank shaft, the radial passage being connected with an axial passage 53. The axial passage 50 is connected by a radial passage 54 with an annular chamber 55 formed by a channel ring 56, this channel ring having perforations 57 connecting the inner channel with an outer space 57^a. The ring is formed in a stuffing box 58 with a packing 58^a at each side of the ring. A pipe 59 leads from the stuffing box and in communication with the space 57^a to a passage 60 in the valve chest. The passage 60 extends through the face of the valve seat by way of a port 61. The axial passage 53 extends through the end of a crank shaft and communicates with a chamber 62 formed in a fitting 62^a. A screw 63 extends through a plate 64 in a socket 65 in the fitting 62^a. The plate 64 extends from the engine frame. A pipe 66 extends from the fitting and is in communication with the chamber 62 and leads to a passage 67 in the valve chest. A port 68 leads from the passage 67 through the valve seat in the throttle valve chamber. An exhaust port 69 extends from the seat of the throttle valve to any convenient place of exhaust.

Starting with the throttle valve in the closed position of Fig. 5 the port 68 is uncovered thus putting fluid into the cylinder 47 and throwing the rock shaft and eccentric to the positions indicated in Fig. 3. In

other words, the throttle valve will be normally set in this way although it may be normally held for a reversal. With the parts in the position shown in Fig. 5 the operating handle 34^c will have the position of *a* in Fig. 2. As the operating handle is moved to the position *b* the throttle valve is opened as indicated in Fig. 6 and with the eccentric set as indicated the engine will be driven in a forward direction. As the handle is moved to the point *c* bringing the position of the valve to that shown in Fig. 11 the port 61 will be uncovered throwing the rock shaft to the position shown in Fig. 9 and carrying the eccentric to the reverse position. A further movement of the operating levers carries the throttle valve to the position shown in Fig. 12 admitting steam to the engine and the engine will proceed in a reverse direction. It will be understood that the port 35 in the valve 34 is brought into register with the port 13 and with the forward direction of the engine as shown in Fig. 6 and the port 36 with the port 13 in the reverse position as shown in Fig. 12.

It will be observed that in Figs. 8 and 13 there is shown diagrammatically the position of the eccentrics and cranks. In these diagrams the axis of the carrier is indicated at *e*, the axis of the eccentric at *f*, the center of the crank shaft *g* at *g*, and the cranks at *h* and *i*. As the rock shaft 42 is swung the center, or axis *f* is swung across the crank shaft, thus giving the proper position to the eccentric with relation to the lead and lap of the valve.

What I claim as new is:

1. In a fluid actuated engine, the combination with the valve operating parts comprising a cylinder, a piston, engine valve, crank and crank shaft, connections between the crank and piston, an eccentric, and connections between the eccentric and engine valve, of a fluid actuated mechanism mounted on the shaft controlling the position of the eccentric comprising a rock lever swinging the eccentric to reverse the same; and a piston and cylinder means operating the rock lever through fluid pressure in both directions.

2. In a fluid actuated engine, the combination with the valve operating parts comprising a cylinder, a piston, engine valve, crank and crank shaft, connections between the crank and piston, an eccentric, and connections between the eccentric and engine valve, of a fluid actuated mechanism mounted on the shaft controlling the position of the eccentric comprising fluid pressure means throwing the eccentric under fluid pressure in both directions and holding the same under fluid pressure in forward and reverse positions during the power effort of the engine, said means comprising a rock lever,

a cylinder at each end of the rock lever, pistons in each cylinder, and connections between the pistons and the rock lever.

3. In a fluid actuated engine, the combination with the valve operating parts comprising a cylinder, a piston, engine valve, crank and crank shaft, connections between the crank and piston, an eccentric, and connections between the eccentric and engine valve, of a fluid actuated mechanism mounted on the shaft controlling the position of the eccentric comprising a rock lever swinging the eccentric to reverse the same; and a piston and cylinder means operating the rock lever through fluid pressure in both directions, and devices comprising ways in the engine shaft conveying pressure fluid to the means.

4. In a fluid actuated engine, the combination with the valve operating parts comprising a cylinder, a piston, engine valve, crank and crank shaft, connections between the crank and piston, an eccentric, and connections between the eccentric and engine valve, of a fluid actuated mechanism mounted on the shaft controlling the position of the eccentric comprising fluid pressure means throwing the eccentric under fluid pressure in both directions and holding the same under fluid pressure in forward and reverse positions during the power effort of the engine, said means comprising a rock lever, a cylinder at each end of the rock lever, pistons in each cylinder, and connections between the pistons and the rock lever; and devices comprising ways in the shaft conveying pressure fluid to said cylinders.

5. In a fluid actuated engine, the combination with a cylinder, a piston, an engine valve, a crank, a shaft driven by the crank, connections between the crank and piston, an eccentric mounted on the shaft, and connections between the eccentric and engine valve, of a fluid actuated mechanism controlling the position of the eccentric comprising fluid pressure means throwing the eccentric under fluid pressure in both directions; two control conduits leading to the pressure means; a valve mechanism controlling the conduits; and a throttle valve actuated with the valve mechanism opening the throttle after the opening of the valve mechanism in both directions.

6. In a fluid actuated engine, the combination with a cylinder, a piston, an engine valve, a crank, a shaft driven by the crank, connections between the crank and piston, an eccentric mounted on the shaft, and connections between the eccentric and engine

valve, of a fluid actuated mechanism controlling the position of the eccentric comprising fluid pressure means throwing the eccentric under fluid pressure in both directions; two control conduits leading to the pressure means; a valve mechanism controlling the conduits, said valve mechanism comprising a valve opening one conduit by a movement in one direction and the other conduit by a movement in the opposite direction; and a throttle valve acting with the valve mechanism in both directions and effecting an opening of the throttle with a movement in either direction following the opening of the conduits.

7. In a fluid actuated engine, the combination with a cylinder, a piston, an engine valve, a crank, a shaft driven by the crank, connections between the crank and piston, an eccentric mounted on the shaft, and connections between the eccentric and engine valve, of a fluid actuated mechanism controlling the position of the eccentric comprising fluid pressure means throwing the eccentric under fluid pressure in both directions; two conduits leading from the means; a controlling valve mechanism having a controlling valve seat to which the conduits are ported and a port leading to the engine; and a sliding throttle valve having ports adapted to open said conduits alternately and to open the port to the engine with the opening of either conduit, the opening of the port to the engine following the opening of a port to a conduit.

8. In a fluid actuated engine, the combination with a cylinder, a piston, an engine valve, a crank, a shaft driven by the crank, connections between the crank and piston, an eccentric mounted on the shaft, and connections between the eccentric and engine valve, of a fluid actuated mechanism controlling the position of the eccentric comprising fluid pressure means throwing the eccentric under fluid pressure in both directions; two conduits leading from the means; a controlling valve mechanism having a controlling valve seat to which the conduits are ported and a port leading to the engine; and a sliding throttle valve having ports adapted to open said conduits alternately and to open the port to the engine following the opening of either conduit, said valve having means exhausting one of the conduits as the other conduit is opened.

In testimony whereof I have hereunto set my hand.

CLARENCE B. WESTON.
